Henry A. Weihmann,
By his Atty.

UNITED STATES PATENT OFFICE.

HENRY A. WEIHMANN, OF PHILADELPHIA, PENNSYLVANIA, ASSIGNOR TO
SIMONS, BROTHER & CO., OF SAME PLACE.

DESIGN FOR A CANE OR UMBRELLA HANDLE.

SPECIFICATION forming part of Design No. 19,967, dated July 1, 1890.

Application filed April 15, 1890. Serial No. 348,089. Term of patent 3½ years.

To all whom it may concern:

Be it known that I, HENRY A. WEIHMANN, a citizen of the United States, residing in Philadelphia, in the county of Philadelphia and 5 State of Pennsylvania, have invented and produced a new and original Design for Cane or Umbrella Handles, of which the following is a specification, reference being had to the accompanying drawing, forming part thereof.

10 In the drawing is shown a perspective view of a cane or umbrella handle illustrating my new design.

15 A is the body part, and is formed substantially of the shape shown, having the enlarged upper part B and the enlarged lower part C, the former being the greater in diameter. The upper part of the body is depressed, as at D. The sides of the body part are relieved by the vertical ornamental portions E, 20 the upper ends of which unite in the depressed top D.

F is the base portion and connects directly to the body portion, and is provided with the ornamental points H, substantially as shown. The handle is mounted on the bottom by an 25 annular band of plain metal G.

The handle is made of any suitable material.

Having now described my new design, what I claim as new, and desire to secure by Letters Patent, is—

The design for cane or umbrella handles, substantially as herein described and shown.

In testimony of which invention I have hereunto set my hand.

HENRY A. WEIHMANN.
